DESIGN FOR A CAN OPENER

Frank F. Topping, Muskegon Heights, Mich.

Application February 12, 1945, Serial No. 117,893

Term of patent 7 years

(Cl. D22—2)

To all whom it may concern:

Be it known that I, Frank F. Topping, a citizen of the United States, residing at Muskegon Heights, in the county of Muskegon and State of Michigan, have invented a new, original, and ornamental Design for a Can Opener, of which the following is a specification, reference being had to the accompanying drawing, forming part thereof.

Fig. 1 is a perspective view of the can opener embodying my new design, and

Fig. 2 is a perspective view of the opposite sides of the same.

I claim:

The ornamental design for a can opener, substantially as shown.

FRANK F. TOPPING.
